BED OR SIMILAR SPRING

Arthur L. Day, Bangor, Maine

Application February 4, 1941, Serial No. 377,392

1 Claim. (Cl. 5—266)

The invention relates to a bed or similar spring of the general type having a series of vertical coiled springs mounted on supporting means carried by a base frame, and at their upper ends interconnected and connected with a marginal top frame.

One object of the invention is to provide a novel and advantageous yieldable construction for supporting the vertical coiled springs.

With the foregoing in view, the invention resides in the novel subject matter hereinafter described and claimed, description being accomplished by reference to the accompanying drawings.

Figure 1 is a bottom plan view showing one end portion of the spring.

Figure 2 is an enlarged bottom plan view partly broken away.

Figure 3 is a detail horizontal sectional view looking upwardly.

Figure 4 is a perspective view showing a number of the vertical coiled springs and their supporting and securing means.

Preferred features of construction have been illustrated and will be rather specifically described, with the understanding, however, that within the scope of the invention as claimed, variations may be made.

A base frame B is provided, said base frame being of rectangular form and being preferably constructed from angle metal. A central longitudinal member 8 is secured to the end bars of the base frame B and may well be formed from two pieces of angle metal welded together, said central member being tied to the side bars of said base frame by transverse bars 9 disposed at suitable intervals, these bars 9 being also preferably of angle metal.

Transverse spring-supporting wires 10 are disposed in uniformly spaced relation between the sides of the base frame B and the central member 8, the ends of said wires 10 being connected with said sides of said base frame and said central member, by coiled tension springs 11. Longitudinal rows of vertical coiled springs 12 are supported by the wires 10 and the base convolutions of these springs of each row are in contiguous relation with each other at diametrically opposite points, and the wires 10 are substantially tangential to said base convolutions at their points of contiguity. The base convolutions of the springs 12, in question, are connected with the wires 10 by means of pig-tail springs 13 which surround said wires and extend longitudinally thereof. The end portions of these

5 pig-tail springs extend beyond the wires 10, adjacent the coiled tension springs 11 and said end portions are used to connect the base convolutions of other rows of coiled springs 14 at the longitudinal sides of the spring structure over the side bars of the base frame B. The intermediate portions of the same springs 13 are used to connect the base convolutions of a central row of springs 15, the various springs 12, 14 and 15 being all vertically disposed and preferably of more or less hour-glass form.

10 At their upper ends, the springs of the various rows (12, 14 and 15) are connected by transverse pig-tail springs 16, and the outermost of the springs 12 and 14, over the side and end bars of the base frame B, are connected by other pig-tail springs 17 with a rod 18 bent into rectangular form. This rod 18 and the pig-tail springs 17 support a rectangular top frame T which is 15 preferably formed from angle metal, with one horizontal inwardly projecting flange 19 and one vertical downwardly projecting flange 20, the rod 18 being secured to the flange 19 by headed studs 21 shown more particularly in Fig. 3. The numerals 22 to 27 and 34 and the letter L denote 20 elements forming no part of the invention herein claimed.

25 From the foregoing, taken in connection with the accompanying drawings, it will be seen that 30 novel and advantageous provision has been made for carrying out the objects of the invention. The bottom structure of the spring effectively supports and anchors the various vertical coiled springs, yet will yield as required under load, and 35 due to the central longitudinal member 8, the spring will not sag in the center.

As excellent results may be obtained from the details disclosed, they are preferably followed. However, within the scope of the invention as 40 claimed, variations may of course be made.

What is claimed is:

In a bed or similar spring, a rigid base frame 45 having side and end bars and a central longitudinal bar, parallel uniformly spaced transverse wires extending from said central bar to said side bars, tension springs connecting the ends of said wires with said side bars and said central bar, two longitudinal rows of vertical coiled springs disposed over said side bars, a third longitudinal row of vertical coiled springs disposed 50 over said central bar, the base convolutions of the coils of any of said rows being contiguous to each other adjacent said tension springs, additional longitudinal rows of vertical coiled springs over said transverse wires, the base convolutions

of the springs of any of said additional rows being contiguous to each other adjacent said transverse wires, and transverse pigtail springs surrounding said transverse wires and each extending from one of said side bars to the other, the end portions of said pigtail springs being disposed over said side bars and embracing the contiguous portions of the base convolutions of said

5 two rows, the central portions of said pigtail springs being disposed over said central bar and embracing the contiguous portions of the base convolutions of said third row, said pigtail springs also embracing the contiguous portions of the base convolutions of said additional rows.

ARTHUR L. DAY.
